UNITED STATES PATENT OFFICE.

JOHN P. BETHKE, OF MILWAUKEE, WISCONSIN, ASSIGNEE TO DINGS MAGNETIC SEPARATOR CO., OF MILWAUKEE, WISCONSIN, A CORPORATION OF WISCONSIN.

MAGNETIC-PULLEY SEPARATOR.

1,286,511.

Specification of Letters Patent.

Patented Dec. 3, 1918.

Application filed January 31, 1918. Serial No. 214,568.

To all whom it may concern:

Be it known that I, JOHN P. BETHKE, a citizen of the United States, and resident of Milwaukee, in the county of Milwaukee and State of Wisconsin, have invented new and useful Improvements in Magnetic-Pulley Separators, of which the following is a description, reference being had to the accompanying drawings, which are a part of this specification.

The invention relates to magnetic separators and more particularly to that class of separators in which a magnetic pulley or drum is used in connection with a conveyer belt passing over said pulley or drum and carrying the material to be separated.

Heretofore in separators of the magnetic pulley type it has been necessary to enlarge or increase the size of the drum to increase the capacity of the machine. The object of the present invention is to provide a means used in connection with the magnetic pulley type of separator to increase the capacity of the machine for any given size of magnetic pulley and also to produce a machine of increased efficiency.

A further object of the invention is to provide means by which the separation of magnetic from non-magnetic material in the magnetic pulley type of separator is more positive than that heretofore used.

Another object of the invention is to provide an extended magnetic field ahead of the magnetic pulley for the purpose of magnetically charging the magnetic material before it comes within the sphere of magnetic influence of the magnetic pulley to thereby overcome the initial reluctance of the magnetic material and thus facilitate its separation from the non-magnetic material while passing over the magnetic pulley.

Another object of the invention is to utilize for magnetic separation that part of the magnetic field of the magnetic drum or pulley which lies between the upper and lower portions of the conveyer belt.

Another purpose of the invention is to provide an extended field into which the material to be separated may enter, and which is ahead of the magnetic drum or pulley to produce a downward pull on the magnetic particles as they pass over the belt and also having a tendency to turn these magnetic particles so that their poles will be trans-

verse of the conveyer belt to insure a positive separation.

The invention further consists in the several features hereinafter set forth.

In the drawings:

Figure 1 is a plan view of the magnetic separator embodying the invention;

Fig. 2 is a side elevation of the device;

Fig. 3 is a transverse sectional view taken on the line 3—3 of Fig. 2, parts of the pulley being broken away to show the coils;

Fig. 4 is a section taken on the line 4—4 of Fig. 2;

Fig. 5 is a detail view of a modified form of the invention;

Fig. 6 is a section taken on the line 6—6 of Fig. 5;

Fig. 7 is a detail view of the magnetic pulley and of the separator showing a different arrangement of the coils from that of Fig. 1;

Fig. 8 is a section taken on the line 8—8 of Fig. 7;

The magnetic pulley 8 is of usual construction and is mounted upon the shaft 9. This pulley is provided with a series of disks 10 mounted upon the shaft 9 and serving as pole pieces. Coils 10' mounted upon the shaft 9 between said pole pieces are so wound that the pole pieces will be of alternate opposite polarity as indicated in Figs. 3, 6 and 8 and said coils are each surrounded by rings 11 preferably of non-magnetic material to serve as a protection for the coils. The shaft 9 is provided at one end with the usual collector ring 12 for conveying the energizing current to the coils 10' of the pulley and said current is conducted through live wires 13 to brushes 12' bearing upon the collector ring 12.

A belt 14, preferably of rubber or other non-magnetic material, serves as a conveyer for the material to be separated. The material is fed to said belt through a hopper 15 or any other suitable means. The belt extends over the magnetic pulley 8, and also over a pulley or drum 16. The shafts of these pulleys 8 and 16 are supported in any suitable manner and the shaft 9 is rotated from any suitable source of power, the shaft 9 being rotated to move the belt forwardly to carry the material upon the top of the conveyer over the magnetic pulley. As is usual in machines of this kind the non-magnetic material drops vertically from the

outer surface of the belt while passing over the magnetic pulley while the magnetic material adheres to the belt until it moves out of contact with the lower portion of the pulley and as the belt itself is of non-magnetic material, the magnetic material will drop therefrom into a receiver (not shown) immediately after the belt leaves the pulley surface.

10 With the usual type of magnetic pulley separator, the pulley alone accomplishes the separation but when said pulley is run at a high speed to increase the capacity of the machine I have found that the material cannot be magnetically charged quick enough for a given size of pulley to accomplish efficient magnetic separation and consequently for increased capacity the size of the magnetic pulley would have to be increased.

15 20 To overcome this difficulty, I provide a magnetic field ahead of the pulley into the magnetic influence of which the material to be separated comes before it passes over the magnetic pulley whereby the capacity of the machine is increased for any given size of pulley and also the separation efficiency of the machine increased.

In Figs. 1 to 4 inclusive this magnetic field is created by auxiliary pole pieces 17 which are of like polarity to the adjacent pole pieces of the magnetic pulley. The ends 18 of the auxiliary pole pieces nearest to the magnetic pulley are shaped to conform to the surface of the magnetic pulley so as to provide an uninterrupted magnetic zone. These pole pieces 17 have pole shoes or polar projections 19 lying beneath the belt and extending lengthwise thereof and core portions 20 which are connected together at 40 their lower ends by a yoke 21 which serves to complete the magnetic circuit. Coils 20' surrounding the cores 20 are provided for energizing the auxiliary pole pieces and are so wound as to magnetically charge the pole pieces so that they will be of alternate opposite polarity and of like polarity to the poles of the magnetic pulley adjacent to them. These coils are shown connected up in series with each other and through wires 21' to 50 the live wires 13 though they may be separately energized or connected up to a different source of current than that for the pulley, as will be readily understood by those skilled in this art.

55 With this construction the energization of the coils produces a magnetic field ahead of the pulley as the magnetic lines of force pass from one polar projection to the other of opposite polarity, said lines of force creating a magnetic field above the belt ahead of the pulley which draws down the magnetic material into close contact with the belt, and also magnetically influences the magnetic material before the material enters the magnetic field produced by the pulley and there-

by overcomes the reluctance of such material before it enters into the magnetic influence of the magnetic pulley. Thus the magnetic material enters the magnetic pulley field in a partially or wholly saturated condition so that the magnetic pulley can be run at a higher speed than those heretofore employed, as in the former constructions when the pulleys are speeded up, the material attains a considerable momentum which cannot be overcome by the usual magnetic pulleys nor can the reluctance of the material be overcome.

In Figs. 5 and 6 I show auxiliary pole pieces 22 which are of similar polarity to that of the adjacent pole pieces of the magnetic pulley. The ends 22' of these pole pieces nearest the magnetic pulley are of considerable area and are shaped to conform to the surface of the magnetic pulley. In 85 this construction no magnetizing coils are used but the magnetic field along the rear surface of the pulley is used to induce magnetism in the pole pieces 22. These pole pieces 22 have their sides 23 tapered so as 90 to converge the magnetic lines of force toward their tops 24 and to provide against loss between the surfaces. The magnets 22 are held in position between the upper and lower portions of the belt 14 by means of 95 rods 24' which may be secured to any suitable support.

In Figs. 7 and 8 I show another magnetic field formed by pole pieces 25 similar to the pole pieces 22 just described and of similar 100 polarity to the adjacent pole pieces of the magnetic pulley. These pole pieces are energized by horizontally disposed coils 26 which are provided with cores 27 extending between the pole pieces and a supporting 105 rod or shaft 28 is used to carry the coils and pole pieces. The coils are connected up in any suitable manner to a source of current.

With any of these constructions it will be noted that the magnetic field produced by the energized magnets ahead of the field of the magnetic pulley will effect the magnetic material passing through said field on the conveyer on its way to the magnetic pulley. That portion of the material which is magnetic will be magnetized or rendered more readily subject to the magnetic action of the pulley because the reluctance of this material is overcome before it reaches the magnetic influence of the pulley. This action will therefore permit of running the pulley at a higher speed, and with better or more positive results because of the more thorough saturation of the material. This action further has a tendency to turn the magnetic particles on 110 the belt so that their poles will be transversely of the belt to insure a more positive separation, as for instance if the magnetic material is in the form of a rod when the rod runs lengthwise of the belt it is apt to 115 120 125 130

fall off the pulley along with the non-magnetic material, but when it is turned transversely of the belt it will be held until the belt leaves the pulley.

5 It will also be noted that in all the forms here shown that part of the magnetic field of the magnetic drum which lies between the upper and lower portions of the conveyer belt is utilized to produce an induced 10 magnetism in the auxiliary magnets and this is particularly true of the constructions shown in Figs. 5 to 8 inclusive.

I am aware that the particular constructions herein shown and described are capable of some changes and I therefore desire it to be understood that such variations in construction as come within the scope of the appended claims I deem to be within the spirit of my invention.

20 What I claim as my invention is:

1. In an annular magnetic separator, the combination with a magnetic pulley having magnetic poles of alternate opposite polarity and a conveyer running over said pulley, 25 of auxiliary magnets having poles disposed immediately adjacent the poles of the magnetic pulley and being of similar polarity to said poles, said magnets being disposed beneath the conveyer directly in front of the 30 pulley, and means for energizing said magnets.

2. In a magnetic separator, the combination with a magnetic pulley having vertically disposed magnetic poles of alternate 35 opposite polarity and a belt running over said pulley, of auxiliary magnets having poles extending lengthwise of the belt and disposed beneath the upper run of the belt immediately adjacent the magnetic poles of 40 said pulley and being of similar polarity to said poles, and means for energizing said auxiliary magnets.

3. In a magnetic separator, the combination with a magnetic pulley having vertically disposed magnetic poles of alternate 45 opposite polarity and a belt running over said pulley, of auxiliary magnets having lengthwise extending pole pieces with one of their ends shaped to conform to the contour of the outer surface of the pulley and 50 disposed immediately adjacent the poles of said magnetic pulley and being of similar polarity thereto, said auxiliary magnets being disposed in front of the pulley between the upper and lower run of the belt and 55 within the magnetic influence of the pulley and having a portion of the pole pieces disposed beneath the belt and in close proximity thereto, and means for energizing said auxiliary magnets to create a magnetic field 60 ahead of the magnetic pulley to facilitate separation of the magnetic from the non-magnetic material carried by the belt.

4. In a magnetic separator, the combination, with a magnetic pulley having spaced 65 apart annular pole pieces and coils interposed between said pole pieces to energize said pole pieces so that they will be of alternate opposite polarity and a belt running over said pulley, of auxiliary magnets having 70 polar projections disposed directly beneath the upper run of the belt in close proximity to said pulley, said polar projections being disposed in line with the pole pieces of the magnetic pulley and being of similar 75 polarity and influenced thereby, and coils for energizing said auxiliary magnets to create a magnetic field ahead of that created by the magnetic pulley to overcome the magnetic reluctance of the magnetic material 80 passing over the belt before said material enters the magnetic field of the pulley.

In testimony whereof I affix my signature.
JOHN P. BETHKE.
